US00D610089S

(12) **United States Design Patent**
Mack

(10) **Patent No.:** **US D610,089 S**
(45) **Date of Patent:** **** Feb. 16, 2010**

(54) **BATTERY**

(75) Inventor: **Robert J. Mack**, Milwaukee, WI (US)

(73) Assignee: **Johnson Controls Technology Company**, Holland, MI (US)

(**) Term: **14 Years**

(21) Appl. No.: **29/302,068**

(22) Filed: **Jan. 9, 2008**

(51) **LOC (9) Cl.** **13-02**

(52) **U.S. Cl.** **D13/119; D13/103**

(58) **Field of Classification Search** **D13/102–106, D13/110, 118–119, 184; 429/96–100, 163, 429/176**

See application file for complete search history.

(57) **CLAIM**

The ornamental design for a battery, as shown and described.

DESCRIPTION

FIG. 1 is a top perspective view of a battery according to an exemplary embodiment;

FIG. 2 is a top plan view thereof;

FIG. 3 is a first side elevation view thereof;

FIG. 4 is a second side elevation view thereof;

FIG. 5 is a first end elevation view thereof; and,

FIG. 6 is a second end elevation view thereof.

The broken lines shown in FIGS. 1–6 are for illustrative purposes only, and form no part of the claimed design.

The long dash-short dash lines shown in the Figures are for the purpose of illustrating the boundaries of the claimed design and form no part of the claimed design. The bottom view forms no part of the claimed design.

1 Claim, 6 Drawing Sheets
